J. H. SAMPSON.
BOOT TREE.

No. 13,886.

Patented Dec. 4, 1855.

UNITED STATES PATENT OFFICE.

JAMES H. SAMPSON, OF GRAFTON, MASSACHUSETTS.

BOOT-TREE.

Specification of Letters Patent No. 13,886, dated December 4, 1855.

To all whom it may concern:

Be it known that I, JAMES HENRY SAMPSON, of Grafton, in the county of Worcester and State of Massachusetts, have invented 5 an Improved Boat-Tree; and I do hereby declare that the same is fully described and represented in the following specification and the accompanying drawings, of which—

Figure 1, is a side elevation of the same; 10 Fig. 2, a vertical central and longitudinal section of it; Fig. 3, a bottom view of it, and Fig. 4, a rear elevation of it.

In these drawings, the boat tree is shown as composed of three principal parts A, B, 15 C, the leg being formed in two sections, A, B, and having the foot or part C connected to the portion B, by a vertical, dovetailed joint or connection as seen at D, such joint being so made as to permit the leg to 20 be easily detached from or attached to the foot part, C, when the latter is placed within the foot of a boot. The two portions A and B, of the leg are formed and arranged with respect to one another as shown in the 25 drawings and they have mechanism applied to them by which their distance asunder may be varied, or they may be pressed apart from one another, when they are inserted in the leg of a boot. The said mechanism is 30 composed of three levers F, F', G, which are arranged within the back portion, A, and so as to work respectively on fulcra H, I, K as seen in Fig. 2. The upper one of these 35 levers extends out of the back portion A, or through a mortise L formed in it as seen in Figs. 2, and 4.

The upper end of the middle lever rests against the inner end of a screw or bearer, M, arranged and screwed into the upper 40 part of the front portion B as seen in Fig. 2, the lower end of said lever lapping by the upper end of the lever, G, as seen in said figure. The lower end of the lever, G, rests against the lower part of the front portion 45 or section B. By turning downward the lever, E, such motion to the levers F and G, will be produced as will cause the two sections, A, and B, to move apart from one another. In order to retain them in any de- 50 sirable position or distance asunder, the lever, E, is provided with a projection or lip, a, arranged on its side and made to work into any one of the notches of a toothed

rack, b, arranged as seen in Fig. 4, sufficient lateral play being allowed to the lever in 55 order to enable the projection to be worked into and out of the notches as occasion may require.

A spring lever catch, O, is applied to the front section B, or is arranged therein as 60 seen in Fig. 2. It has at one end a stud or projection, c, which passes through the female portion of the dovetail and is made to enter a recess, d, formed in the male portion of said dovetail as seen in Fig. 2. The upper part of the lever catch rests against a spring, U. When the two parts A and B are closed upon one another, the pressure 65 of the part A upon the upper arm of the lever catch will prevent the stud of said catch from entering the aforesaid recess, but whenever the two parts A, and B, are separated or forced asunder, the spring lever catch will be free to be moved by its spring and so as to lock the foot C, to the leg por- 70 tion B. 75

A journal, R, extends from the upper part of the portion A. When the boot tree is in use, the said journal is inserted in a suitable socket piece or bearing affixed to a 80 bed or table and serving with the journal to maintain the boot-tree in an upright position as well as to enable it to be rotated or turned around as occasion may require while it is so sustained. In order to cover the 85 joint between the two portions A and B, the front one has two lap plates S, T, affixed to it and made to extend over the rear portion, A, as seen in the drawings.

In using the tree, the foot portion is put 90 in the boot; next the leg parts are passed into the leg of the boot and connected to the foot by the dovetail. This done, the lever E is to be turned down until the sections A, B of the leg are pressed apart to the extent that may be necessary in order to true 95 the boot leg or mold it into shape. By means of the screw in the upper part of the front section the proportions of the leg may be varied or such leg may be made 100 wider at top after the parts A, and B have been moved asunder by the three levers E, F and G.

What I claim as my invention is—

1. The combination and arrangement of 105 the three levers and the screw M applied

to the two sections A and B of the tree and made to operate together substantially as specified.

2. I also claim the combination of the
5 spring lever catch with the foot, C, and front section B, in the manner described and for the purpose specified.

In testimony whereof I have hereunto set my signature this third day of October A. D. 1855.

JAMES HENRY SAMPSON.
